UNITED STATES PATENT OFFICE.

HARRY F. BINKLEY, OF SIDNEY, OHIO, ASSIGNOR OF ONE-HALF TO GIDEON E. CYPHERS, OF SIDNEY, OHIO.

MECHANISM FOR SIMULTANEOUSLY ADJUSTING THE WHEELS AND BRUSH OF A VACUUM CARPET-CLEANER.

1,119,393

Specification of Letters Patent. Patented Dec. 1, 1914.

Application filed May 15, 1914. Serial No. 838,719.

To all whom it may concern:

Be it known that I, HARRY F. BINKLEY, a citizen of the United States, residing at Sidney, in the county of Shelby, and State of Ohio, have invented certain new and useful Improvements in Mechanism for Simultaneously Adjusting the Wheels and Brush of a Vacuum Carpet-Cleaner; and I do hereby declare the following to be a full, clear, and exact description of the invention, such as will enable others skilled in the art to which it appertains to make and use the same.

This invention relates to mechanism for simultaneously adjusting the wheels and brush of a vacuum carpet cleaner.

In vacuum cleaners of the type referred to it is necessary to adjust the brush and wheels for different grades of carpet, matting, etc., and it is the object of the present invention to provide a mechanism whereby the wheels and brush may be simultaneously adjusted through the medium of a common means and the necessity of a double operation in effecting such adjustment thereby obviated.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a front elevation of a vacuum cleaner nozzle having the invention associated therewith; Fig. 2, an end view of what is shown in Fig. 1; Fig. 3, a section on the line 3—3 of Fig. 1; Fig. 4, a section on the line 4—4 of Fig. 2; and Fig. 5, a perspective view of the adjusting frame.

Referring to the drawings A indicates the nozzle of a vacuum cleaner which includes the usual end portions 10 and 11. These end portions 10 and 11 are provided respectively with corresponding recesses 12 and 13' opening through the bottom edges of said end portions.

Pivoted eccentrically on the end portions 10 and 11, as at 10', are disks 13 and 14 respectively, said disks being mutually con-

nected by a bar 15. The disks 13 and 14 are preferably constructed from a metal blank as shown in Fig. 5.

Journaled in the disks 13 and 14 respectively are the trunnions 16 and 17 of a rotary brush 18, said trunnions being disposed eccentrically with respect to the disk and the trunnion 16 having fixed thereon a gear 19. It will be noted that the trunnions 16 and 17 are movable in the recesses 12 and 13' respectively toward and away from the mouth of the nozzle A as the disks 13 and 14 are moved on their pivots.

Projecting outwardly from the center of each disk 13 and 14 is a journal stud 20 and rotatably mounted on these studs are traction wheels 21 and 22 respectively. The traction wheel 21 has fixed to its inner side a gear 23 which meshes with the gear 19 and whereby the rotation of the traction wheel 21 will impart rotation to the brush 18.

Threaded in the bar 15 is a locking screw 24 which is adapted to be selectively engaged in recesses 25 formed in the wall of the nozzle A.

By disengaging the screw 24 from a given recess 25 it will be obvious that the disks 13 and 14 can be swung on their pivots to effect simultaneous adjustment of the brush 18 and wheels 21 and 22, the relation between the brush and wheel always being maintained the same. After the desired adjustment of the wheel and brush is attained the screw 24 is engaged in the necessary recess 25 to lock the disks 13 and 14 against pivotal movement.

What is claimed is—

1. In a device of the class described the combination with a vacuum cleaner nozzle, disks eccentrically pivoted on the ends of said nozzle, a brush disposed within the nozzle and journaled in said disks, traction wheels rotatably mounted on the disks, connections between one of said traction wheels and the brush for rotating the latter, and means for simultaneously swinging the disks on their pivots.

2. In a device of the class described, the combination with a vacuum cleaner nozzle having recesses in its end portions respectively, disks eccentrically pivoted on the ends of said nozzle, a bar connecting said disks, a brush disposed within the nozzle

and journaled in said disks, traction wheels rotatably mounted on the disks, connections between one of said traction wheels and the brush for rotating the latter, and a screw mounted in said bar and selectively engageable in recesses formed in the wall of the nozzle to lock the disks against pivotal movement.

In testimony whereof, I affix my signature, in the presence of two witnesses.

HARRY F. BINKLEY.
